METHOD FOR MAKING PIPE COUPLING PARTS

James F. King, Cranston, R. I.

Application August 24, 1935, Serial No. 37,663

5 Claims. (Cl. 29—157)

This invention relates to a method for making pipe coupling parts which is adapted to form certain of the coupling members more readily and with less expenditure of time and labor than has been possible by the methods heretofore employed. One object of the invention is to provide a method for forming pipe coupling parts more expeditiously and at less cost than has been possible previously by initially forming certain of said parts together and then shaping and separating them through operative steps which combine certain of the operations to effect a saving in time and labor.

Another object of the invention is to provide a method for forming pipe coupling parts by casting or otherwise shaping two of the parts together at the same time as an integral structure and then shaping and separating the parts thus formed to produce coupling members.

Other objects and advantages of the invention relate to various improved method steps and arrangements of steps in carrying out the process as will be more fully set forth in the detailed description to follow.

Referring to the drawing:—

Fig. 1 is a longitudinal sectional view through a casting such as is adapted to be shaped to form a coupling rim and one of the members of a pipe coupling.

Fig. 2 is a similar view of the casting showing the same after threads have been cut upon the inner surfaces of opposite ends and after the formation of a shoulder adjacent to the thread upon that portion of the casting having the larger diameter, and illustrating the position of a cutting tool with respect to the shape in the position of these elements prior to the separation of the shape into coupling members.

Fig. 3 is a view similar to Figs. 1 and 2, showing the coupling member and coupling rim member when separated from each other, as in the position occupied by them after the completion of the cutting operation indicated in Fig. 2.

Fig. 4 is a longitudinal sectional view through a coupling showing the position of the parts when assembled, and.

Fig. 5 is a side elevational view of a completed coupling with the parts in assembled relation.

In the embodiment of the invention illustrated herewith, 1 designates an integral, hollow, two-diameter casting of generally cylindrical or terete shape which may be said to comprise a portion 2 of a large diameter and a portion 3 of smaller diameter, the external diameter of the portion

3 being equal to or slightly less than the internal diameter of the portion 2 throughout the greater part of its extent, whereby the portion 3 of smaller diameter is capable of being inserted within the portion 2.

The shape 1 may be formed by casting, forging, swaging, or in any other suitable manner. In either case the portion 2 of enlarged diameter is of suitable size for forming the rim member of a pipe coupling, while the portion 3 is of such size as to form one of the internal coupling members and be capable of being inserted within the portion 2 and held therein by interengaging means carried by the rim member and coupling member respectively to form together part of a 15 pipe coupling.

After the formation of the shape 1 as above described, the shape may be subjected to the necessary cutting and turning operation for cutting internal threads 4 and 5 and forming an 20 internal shoulder 6 in the enlarged portion 2. These operations may well be performed before dividing the shape into separate elements substantially along the transverse line 7.

One method by which the shape may be divided into separate parts is by rotating the same against a cutting tool 8, which is provided with a cutting end 9 for cutting through the wall of the shape substantially along the transverse line 7. The tool 8 may also be provided with a suitable shaped cutting edge 10 for forming a seat 11 upon the portion 3, and may have a recess 12 and cutting face 13 for forming an outer shoulder 14 on the portion 3 during the operation resulting in the separation of the parts.

Upon the completion of this operation the shape 1 is separated to form a rim coupling member 15 having internal threads 4 and an internal shoulder 6, and a coupling member 16 having internal threads 5 and an external shoulder 14. 40 The coupling member 16 is also provided with a seating surface 11 adapted to fit against a suitable seating surface 17 formed upon the end of a third coupling member 18 when the parts are assembled, as is shown in Fig. 4 of the drawing. 45

While in the present illustrated embodiment of the structure and in the description relating thereto the rim coupling member 15 and the male coupling member 16 are formed together as an integral structure and then shaped and separated from each other, it is to be understood that the method described comprehends the formation of the rim coupling member 15 and female coupling member 18 together as an integral shape and the formation and separation of these mem- 55

bers after the manner described when desired. In providing an integral shape for the formation of a rim coupling member and female coupling member therefrom the shape of the cutting tool 8 is correspondingly changed, so that the tool 8 may serve merely as a cutting off tool, in which case the seating surface 17 may be formed on the female member by a separate tool moved into operative engagement with the part after the completion of the cutting off operation.

It will be seen upon reference to the drawing that the portions 2 and 3 of the shape 1 are separated along a line which marks substantially the meeting of the two diameters, whereby the rim coupling member 15 and male coupling member 16 thus formed are each of substantially uniform diameter throughout the greater portion of its extent, and the coupling member 16 is of such size as to fit within the rim coupling member 15 so that the external shoulder 14 formed thereon engages with the internal shoulder 6 of the rim coupling member when the parts are assembled.

The method of construction above described provides a simple and effective means for initially forming two parts of a coupling together, which produces a material saving in time and labor while permitting ready handling and manipulation of the composite shape to produce the required members adapted to be interfitted together to form a coupling.

When forming the shape 1 as an integral structure and then cutting and shaping the same prior to its separation into coupling member parts, the integral shape lends itself more readily to the operation of cutting and shaping tools than would be the case with separate elements and permits the carrying out of several cutting and shaping operations without removing the same from a holder, thus maintaining it in properly centered position for the operation of the different tools without requiring resetting.

In the separation of the shape into coupling members by the method above described, and when forming a rim coupling member with a male coupling member 16, the severing of the parts, and the formation of an external shoulder 14 and a suitable seating surface 11 on the coupling member 16 may all be effected together and as a part of a single operation.

What I claim is:

1. The method of making pipe coupling parts which comprises, forming a hollow terete shape having one end portion thereof of a diameter throughout substantially greater than that of the opposite end portion, cutting internal threads in opposite ends of said shape and forming an annular shoulder in the end portion of greater diameter, separating said portions along a line

located substantially at the point joining the two-diametered portions, and forming an external shoulder upon the portion of smaller diameter of a size adapted to fit within the internally threaded part of the portion of larger diameter.

2. The method of making pipe coupling parts which comprises, forming a hollow, two-diametered casting of generally cylindrical form having one portion thereof of an internal diameter substantially equal to the external diameter of 10 a part of the remaining portion, shaping the internal surface of the portion of larger diameter and the external surface of the portion of smaller diameter to form shoulders adapted to interfit, and separating the casting into parts to provide 15 a rim coupling member and a coupling member adapted to fit within said rim coupling member.

3. A method of making pipe coupling parts which comprises, forming a hollow, two-diametered shape in which each of the two-diametered 20 portions are of substantially cylindrical form, shaping the internal surface of one portion to give it an internal diameter substantially equal to the external diameter of the major part of the remaining portion and provide a continuous internal shoulder, shaping the external section of the remaining portion to provide an external shoulder adapted to interfit with the internal shoulder of said first named portion, and separating said portions from each other along a line 30 located adjacent to the juncture of the different diametered portions.

4. The method of making pipe coupling parts which comprises, forming a hollow, two-diametered shape in which each portion of substantially 35 uniform diameter is of generally cylindrical form, forming internal threads adjacent to one end of each portion of substantially uniform diameter, and separating the shape into separate parts along a line located substantially at the meeting line 40 of the portions of different diameters and by the same operation forming an external shoulder and seating surface upon one of said portions.

5. The method of making pipe coupling parts which comprises, forming a hollow terete shape 45 having one end portion thereof of a diameter substantially greater than that of the opposite end portion, cutting internal threads in opposite ends of said shape and forming an annular shoulder in the end portion of greater diameter, separating said portions along a line located substantially at the point connecting the portions of different diameters, and forming a seat upon one end of the portion of smaller diameter for fitting against a similar seat formed upon the end of a 55 coupling member when the parts are arranged in assembled relation to form a pipe coupling.
